INVENTOR

UNITED STATES PATENT OFFICE.

ISIDOR TAHIL, OF NEW YORK, N. Y.

DESIGN FOR A BOX.

SPECIFICATION forming part of Design No. 29,036, dated July 12, 1898.

Application filed March 28, 1898. Serial No. 675,509. Term of patent 7 years.

To all whom it may concern:

Be it known that I, ISIDOR TAHIL, a citizen of the United States, residing in the city, county, and State of New York, have invented 5 and produced a new and original Design for Paper Boxes, of which the following is a description, reference being had to the accompanying drawing, forming part thereof.

The drawing is a perspective view of a box 10 embodying my new design.

The leading or material feature of my design consists in a box of the shape or configuration shown in the accompanying illustration or drawing.

15 A is the top of the box, which projects beyond the heads D, at the front end terminating in a double-inclined or forwardly project-

ing or converging outer edge and at the rear end terminating in a curved outer edge.

C represents the face forming the bottom 20 of the box, which is of less length than the opposite face A, forming the top of the box.

B represents the sides of the box, having curved ends extending from at or near the bottom of the box outwardly beyond the heads 25 or ends of the box to the top of the box.

D represents the heads or flaps.

What I claim is—

The design for a paper box, substantially as herein shown and described.

ISIDOR TAHIL.
